TOGGLE ACTUATED PLIER WRENCH

John Johnson, Brockton, Mont.

Application September 28, 1951, Serial No. 248,684

11 Claims. (Cl. 81—84)

1

This invention relates to pliers or wrenches. More particularly, the invention has reference to an articulated wrench of the type including a pair of pivoted, toggle-actuated jaws capable of being releasably locked to a piece of work.

Conventionally, in wrenches falling within the category referred to the jaws are so pivoted that the work-engaging faces thereof are related angularly to one another in various positions to which the jaws are swung. In this connection, the angle at which one jaw face is disposed relative to the other will vary according to the distance between the faces. The distance between the faces, obviously, will in turn be varied during the use of the tool, and will be established on each occasion of use by the thickness of the particular work piece engaged by the jaw faces. It follows, therefore, that the thickness of the work will determine the angle of the jaw faces to one another, and it is also a fact that the jaws will operate with less efficiency in gripping the work when disposed at one angle relative to one another than they will when disposed at another angle. For example, the angular relation of the jaw faces will in many instances prevent them from engaging a work piece of circular cross sectional configuration at diametrically opposite locations, as a result of which a tendency toward slippage asserts itself.

The present invention has as one important purpose the provision of a plier-wrench which will have pivotally mounted, toggle lever-actuated jaws, thus embodying in the construction the powerful leverage inherent in wrenches of this type, but which will at the same time be so designed as to cause the jaw faces to be disposed in parallel planes in all positions to which the jaws are adjusted relative to one another, thus to eliminate the deficiency noted above as being present in conventional construction.

Additionally, it may be noted that in conventionally constructed wrenches or pliers of the type referred to, locking of the jaws to the work occurs when the toggle commonly embodied in such wrenches passes across a dead center. This is desirable when the wrench is used as a clamp or vise. However, this characteristic is annoying and time-consuming when the tool is used as a ratchet or pipe wrench.

Such a tool is capable of being adjusted, most usually, so that it will not lock, but when so adjusted the greatest advantage thereof is lost, namely, the tremendous leverage exerted by the toggle lever arrangement. Since the pressure required to bring the toggle back across a dead

center and thus unlock it is equal to that exerted during the locking of the toggle, and further since the unlocking pressure must be applied in a reverse direction, it is usually awkward and difficult to perform this operation with the back of the fingers of the hand in which the wrench is held. As a result, it is often found necessary to unlock the wrench with the other hand. In many instances, this represents a decided inconvenience.

10 Accordingly, it is another important object of the present invention to provide a wrench falling within the general category stated, which will have an improved locking mechanism that will be operative only when desired by the user. Thus, 15 when the tool formed in accordance with the present invention is used as a ratchet or pipe wrench, the jaws may be released instantly when pressure on the handles is relaxed even though the tool may be adjusted for maximum gripping power. It is proposed to attain this result 20 through a construction wherein the toggle joint will move close to a dead center so as to obtain a maximum amount of gripping power. However, the movement past a dead center will be prevented by a stop means embodied in the locking mechanism so that automatic locking of the jaws 25 is ordinarily prevented. When, however, it is desired to lock the jaws to the work, a trigger is readily operable by the user to set into operation the locking mechanism which I have devised. Subsequently, simple pressure by the user tending 30 to urge the handles of the tool toward one another is effective to automatically disengage said mechanism. In this way, the tool is readily usable not only as a clamp or vise, but also, as a ratchet or pipe wrench, at the option of the user.

Other objects will appear from the following description, the claims appended thereto, and 40 from the annexed drawing, in which like reference characters designate like parts throughout the several views, and wherein:

Figure 1 is a top plan view in which a portion of one handle has been broken away;

45 Figure 2 is a longitudinal sectional view taken substantially on line 2—2 of Figure 1;

Figure 3 is a longitudinal sectional view taken substantially on line 3—3 of Figure 2;

50 Figure 4 is a longitudinal sectional view taken substantially on line 4—4 of Figure 3;

Figure 5 is an enlarged front elevational view;

Figure 6 is an enlarged transverse sectional view taken substantially on line 6—6 of Figure 2;

55 Figure 7 is an enlarged transverse sectional

view through a portion of the locking mechanism, taken substantially on line 7—7 of Figure 2;

Figure 8 is an enlarged longitudinal sectional view through said portion of the locking mechanism, taken substantially on line 8—8 of Figure 3.

Figure 9 is a side elevational view in which one of the cover plates has been removed, one of the handles being shown partially in longitudinal section; and

Figure 10 is a view similar to Figure 4 and illustrating a modified form.

Referring to the drawings in detail, a handle member 12 has a channeled inner end portion and a tubular outer end portion. Formed in the bight of the inner end portion is a pair of parallel, longitudinal slots 14. These receive the reduced ends 16 of a pair of parallel cover plates 18, said plates being of flat formation and extending from the handle member 12 in parallelism along opposite sides of the tool, substantially to the head end of the tool. For the greatest part of their length, the cover plates 18 are of substantially widened dimensions, so as to enclose protectively and afford a support for the articulated linkage embodied in the device.

The cover plates 18 are fixedly secured to the handle member 12 in any suitable manner, as by rivets, welding, or integral formation with the handle member.

Fixedly mounted in the tubular outer end portion of the handle member 12 is a bushing 20, having an end to end threaded bore in which is threadedly engaged a tubular adjusting screw 22, having right-hand external threads. The adjusting screw projects rearwardly from the handle member 12, and the projecting portion of the screw is integral with or otherwise fixedly connected to a turning knob 24.

The adjusting screw 22 is formed with internal threads engaged by left-hand threads provided upon a toggle holder 25 the free end of which is bifurcated as at 26.

The purpose of this arrangement is to effect faster adjustments and shorter travel of the adjusting screw, and also to provide means adapted to prevent the toggle holder from slipping out of place.

Pivottally connected to the bifurcated end of the screw is one end of an actuating lever 28, which extends obliquely from the handle comprising the handle member 12 and the cover plates 18; and at its other end, has a pivotal connection 30 to a second handle 32.

For clarity in description, the handle first described will be hereinafter referred to as a fixed handle, while the handle 32 will be referred to as a movable handle.

I believe it will be apparent, from the description so far provided, that when the fixed and movable handles are grasped by the hand of a user, pressure exerted by the user tending to press the handles together will be operative to impart movement to the handle 32 longitudinally of the fixed handle in the direction of the head or work-engaging end of the tool. This is so because such pressure will cause movement of the pivotal connection 30 in an arcuate path about the pivotal connection at the other end of the actuating lever 28, toward the left in Figures 2 and 9. Such movement will naturally tend to carry with it the movable handle 32.

The movable handle 32 is integrally formed with a widened inner end portion 34 arranged longitudinally and centrally of the tool as best shown in Figure 6. The outer end portion of

the movable handle, it may be noted, is of channeled formation, to enclose the locking mechanism embodied in the invention, and to be described hereinafter.

5 A pivot pin 36 serves to articulate the inner end portion 34 of the movable handle to one end of a pair of identically formed, parallel lever members 38 of longitudinally curved formation, that embrace the inner end portion 34 of the movable handle at said end thereof.

The lever members 38 together may be termed a main lever and will be so designated herein-after.

The main lever is fulcrumed medially between opposite ends thereof upon a main pivot pin 40 which, as may be noted from Figure 2, is of square cross-section. The pin, as will also be noted from Figure 3, has reduced ends riveted to the respective cover plates 18.

15 It will be appreciated that on shifting of the movable handle 32 to the left in the several figures of the drawing, the main lever will be caused to rock on the main pivot pin 40, so that the end of the main lever remote from the movable handle will be given movement in a reverse direction, away from the work-engaging end of the tool.

20 In Figure 10, there is illustrated a modified form of main pivot, comprising a rivet 42 extending between the cover plates 18 on which is provided a roller 43 on which the main lever is rockably mounted.

25 Pivottally connected to that end of the main lever that moves away from the head of the tool when the handles are pressed together, through the medium of a pivot pin 44, is a connecting link 46. The connecting link 46 is of arcuate formation, and is connected to the main lever at one end, said end extending between the lever members 38.

30 The other end of the connecting link 46 is bifurcated, and has a pivotal connection 48 to a center plate generally designated 50. The center plate 50 is particularly well shown in Figure 4, wherein it is seen that the plate is straddled by the bifurcated end of the link 46, contiguous to the head end of said plate.

35 It will thus be seen that when the main lever is rocked in the manner described above, the link 46 will be shifted in a direction away from the head end of the tool, and will be effective to shift the center plate 50 in the same direction.

40 The center plate 50 is disposed medially between and in parallel relation to the cover plates 18, and at its foot end, is provided with an elongated, longitudinal, closed slot 52 through which extends a flattened guide lug 54. The guide lug 54 extends transversely between the cover plates 18, and is rigidly secured at opposite ends to the inner faces of said plates.

45 In Figure 10, the center plate has a slot 58 slightly wider than the slot 52 corresponding thereto in the first form of the invention, a pin 60 extending transversely between the cover plates 18 and being rigidly secured to said cover plates. The pin 60 extends through the slot 58, and is provided with a roller 62.

50 In both forms of the invention, the center plate, when shifted longitudinally of the tool, has straight line movement, said straight line movement being provided for not only by the provision of the longitudinal slots and guide means extending therethrough, but also through the provision of a second longitudinal slot 64 through which the main pivot extends, the main pivot

thus serving as a second guide means cooperating with the guide means 54 or 62. Slots 52, 64 are in exact parallelism.

Movement of the center plate away from the head end of the tool is against the action of a spring 66, one end of which is engaged with said plate, and the other end of which is engaged by a transverse abutment 68 secured by rivets 70 to the side walls of the channeled handle member 12. Thus, whenever pressure on the fixed and movable handles tending to urge them toward one another is released (and assuming that the locking mechanism is arranged inoperatively) the spring 66, tending to expand, will bias the center plate toward the head of the tool and will therefore tend to normally spread the handles.

At the head end of the center plate 50, transversely spaced pivot pins 72 are provided upon the center plate, said pivot pins serving to articulate to the plate a pair of front toggle links 74.

At their other ends, the toggle links 74 are pivotally connected at 76 to a pair of work-engaging jaws 77, 78 which for purposes of clarity will be referred to as an upper jaw and a lower jaw.

The lower jaw includes a pair of elongated, parallel jaw plates 77 that extend longitudinally of the tool between the cover plates 18, along the lower longitudinal edges of said cover plates. The lower front toggle link extends between and is pivotally connected at 76 to the jaw plates 77, 30 while the upper front toggle link extends between and is pivotally connected to a pair of parallel upper jaw plates 78, that are disposed between and in parallelism with the cover plates 18 adjacent the upper longitudinal edges of said cover plate.

Rigidly connecting the lower jaw plates 77 at the head end of the tool is a serrated, work-gripping jaw face 79. An upper jaw face 80 cooperates with the lower jaw face 79 in gripping a piece of work, not shown, and similarly connects the upper jaw plates 78. Movement of the center plate 50 away from the head end of the tool is effective to impart movement in the same direction to the pivotal connections 72, as a result of which the toggle links 74 will be swung about said pivotal connections, thus to cause movement of the pivotal connections 76 toward one another. This may be readily noted by comparison of Figures 9 and 4. In Figure 9, the jaws are shown in open position, while in Figure 4, the jaws are shown in a closed position. In each of these positions, the jaw faces 79, 80 are in parallel relation.

Disposed between the respective jaws and the cover plates are upper and lower front control links 82. These are pivotally connected at one end to the jaw plates associated therewith through the medium of the pivotal connections 76, and are pivotally connected at their other ends, as at 84, to the cover plates.

Upper rear control links 86 are also disposed between the jaw plates and the cover plates, at the inner end of said jaw plates. These are pivotally connected at one end to the cover plates by pivot pins 88.

The links 86 are associated with the upper jaw plates, and for association with the lower jaw plates, I provide lower rear control links 90 which are pivotally connected at 92 to the cover plates.

Pivotal connections 94 serve to articulate the upper rear control links 86 to the inner ends of the upper jaw plates 78, while corresponding pivotal connections 96 are employed to provide an

articulated connection between the lower rear control links 90 and the lower jaw plates 77.

Rear toggle links are provided, that connect the inner ends of the jaw plates to the center plate 50, so as to cooperate with the front toggle links 74 in shifting the jaw faces toward and away from one another. To this end, upper links 98 are disposed at opposite sides of, and pivotally connected at 100 to the center plate, said links 98 being articulated to the upper jaw plates 78 through the medium of pivotal connections 94. Lower rear toggle links 102 are pivotally joined at 104 to the center plate, and at 96 to the lower jaw plates 77.

Through the provision of the front and rear control links, both jaws are articulated to the fixed handle 12, at locations spaced longitudinally of said handle and jaws. Thus, the pivotal connections 76 of the front control links and the pivotal connections 94, 96 of the rear control links swing about the pivotal connections 84 of the front control links and the pivotal connections 88, 92 of the rear control links when the center plate is shifted away from the head end of the tool, thus to control the movement of the jaws toward and away from one another when said movement is imparted to the jaws by means of the front and rear toggle links 82 and 98, 102 respectively.

It is to be noted that the jaws faces 79, 80 are in exact parallelism with the slots 52, 64. In this connection, it should be understood that although the wrench may be constructed with straight jaws or with jaws offset at angles other than that illustrated, it is essential that said jaw faces and slots all be parallel in any position of the jaws, from a fully closed to a fully open position.

Further, the arrangement which I have devised is such (see Figures 2, 4, 9, and 10) that straight lines drawn between the centers of front pivots 84, 84; rear pivots 88, 92; pivot points 72, 72; and pivot points 100, 104, will each be perpendicular to a straight line drawn parallel to the jaw faces.

Referring now to the locking mechanism embodied in the invention, I provide, at the free end of the movable handle 32, a pivot pin 106 (Figures 7 and 8) whereby there is pivotally mounted upon the movable handle a trigger 108. A spring 110 is coiled about the pivot pin 106, and normally biases the trigger to an inoperative position illustrated in Figure 9.

Limiting movement of the trigger 108 to said inoperative position thereof are stop lugs 112 integrally formed upon the opposite side walls of the movable handle 32, said stop lugs engaging the inner end of the trigger 108.

The trigger 108 is of channeled formation, and extending inwardly from the opposite side walls thereof are pintles 114 on which a block 116 is rockably mounted. The block 116 is provided with a bore receiving a rod 118 slidable in the block in the direction of its own length.

A coiled spring 120 surrounds the rod 118, said spring abutting at one end against the block 116. For the purpose of limiting movement of the rod 118 in one direction, I provide a pair of nuts 122, that are threaded upon the rod at one end thereof.

At its other end, the rod 120 is formed with a flattened head 124 guided during sliding movement of the rod 118 by a cross piece 126, that extends between the side walls of the movable member and is rigidly secured to said movable handle, and by guide lugs 128, that overlie the

head 124 and are also rigidly secured to the movable handle.

At its free end, the head 124 is of beveled formation, and is provided with a transverse notch on its under side, receiving a latch hook 130 formed upon the actuating lever 28 intermediate opposite ends of said lever.

The notch formed upon the head 124 has been designated 132, and is so proportioned as to receive an upturned lip on the hook 130 when the lever 28 and head 124 are positioned as in Figure 2.

A bumper spring 134 is secured within the movable handle 32, and extends longitudinally thereof, said spring being so arranged as to exert upward pressure against the actuating lever 28 when the fixed and movable handles of the tool are pressed together.

In use, the fixed and movable handles are grasped in the hand of a user, and are pressed toward one another, so as to engage the jaws with a piece of work. In this connection, the knob 24 is rotated as necessary, so as to adjust the jaws preliminary to application thereof to the work, the jaws being preliminarily adjusted to such an extent as will cause them to engage the work with the fixed and movable handles spaced apart to the extent illustrated in Figure 2, that is, to an extent as will cause the hook 130 to be engaged by the bumper spring 134.

The spring 110 will previously have urged the trigger 108 to a position in which the head 124 will be disposed fully to the right of the hook 130 when viewed as in Figure 2, when the fixed and movable handles are pressed together. As a result, mere pressure exerted against the handles tending to move them toward one another will cause the jaws to engage the work securely, but will not set the jaw-locking mechanism into operation. However, if the user desires to lock the jaws to the work, it is merely necessary that he engage the trigger 108 with a finger of his hand, to swing the trigger upwardly toward the fixed handle. As a result, the block 116 is swung about the pivot 106, in the direction of the head 124.

This causes the rod 118 to be shifted bodily to the left in Figure 2, to engage the hook 130 and notch 132, and thus lock the jaws to the work.

At such time as it may be desired to release the jaws, the user merely presses the fixed and movable handles toward one another, against the action of the bumper spring 134, so that the hook 130 is lowered out of engagement with the notch 132. The spring 120, tending to expand, biases the block 116 to the right in Figure 2, the block carrying with it the rod 118 and the head 124 so as to disengage the head fully from the hook.

For the purpose of imparting rigidity to the construction of the tool, and to insure the proper spacing of the cover plates 18, a spacer sleeve 136 may be extended between the plates in advance of the handle member 12, said spacer sleeve being mounted upon a rivet 138 rigidly connecting the cover plates.

It is believed clear that the invention is not necessarily confined to the specific use or uses thereof described above, since it may be utilized for any purpose to which it may be suited. Nor is the invention to be necessarily limited to the specific construction illustrated and described, since such construction is only intended to be illustrative of the principles of operation and the means presently devised to carry out said prin-

ciples, it being considered that the invention comprehends any minor changes in construction that may be permitted within the scope of the appended claims.

It is also believed clear that the locking mechanism illustrated and described herein, though illustrated in association with a novel jaw actuating assembly, can be readily applied to any conventional lever-jaw wrench, and will function with full efficiency in wrenches of various types and dimensions.

What is claimed is:

1. A plier-wrench including a fixed handle; a movable handle connected thereto for swinging movement through a path extending longitudinally of the fixed handle, the connection of the handles to one another comprising an actuating lever pivotally attached at its ends to the respective handles; a pair of jaws provided with parallel, work-engaging faces and articulated to the fixed handle for movement into engagement with a work piece, said jaws being respectively extended longitudinally of the fixed handle, the articulated connection of each jaw to the fixed handle comprising a pair of control links of equal length respectively connected pivotally at their opposite ends to and spaced longitudinally of the jaw and fixed handle, said links being arranged for swinging movement of the jaws toward and away from one another while holding the jaw faces parallel; a center plate mounted on the fixed handle to shift longitudinally thereof in a straight line; a linkage between the center plate and the movable handle operative to shift the center plate responsive to movement of the movable handle toward the fixed handle; and toggle means articulated to the center plate and jaws and effective to engage the jaws with the work piece responsive to longitudinal shifting of the center plate.

2. A plier-wrench including a fixed handle; a movable handle, said movable handle being connected to the fixed handle for swinging movement through a path extending longitudinally of the fixed handle; a pair of jaws provided with

parallel, work-engaging faces and articulated to the fixed handle for movement into engagement with a work piece, said jaws being respectively extended longitudinally of the fixed handle, the articulated connection of each jaw to the fixed handle comprising a pair of control links of equal length respectively connected pivotally at their opposite ends to and spaced longitudinally of the jaw and fixed handle, said links being arranged

for swinging movement of the jaws toward and away from one another while holding the jaw faces parallel; a center plate mounted on the fixed handle for straight-line movement longitudinally thereof; an actuating lever constituting means connecting the movable handle to the fixed handle for swinging movement, said actuating lever being pivotally connected at opposite ends to the respective handles and being arranged to swing the movable handle longitudinally of the fixed handle toward the jaws, on exertion of pressure tending to urge the handles toward one another; direction-reversing means connecting the movable handle and the center plate for straight-line movement of the center plate longitudinally of the fixed handle in a direction opposite that given the movable handle; and toggle links articulated to the center plate and jaws and effective to engage the jaws with the

70

75

work piece responsive to said movement of the center plate.

3. A plier-wrench comprising a fixed handle; guide means carried thereby; a movable handle, said movable handle being connected to the fixed handle for swinging movement through a path extending longitudinally of the fixed handle; a pair of jaws provided with parallel, work-engaging faces and articulated to the fixed handle for movement into engagement with a work piece, said jaws being respectively extended longitudinally of the fixed handle, the articulated connection of each jaw to the fixed handle comprising a pair of control links of equal length respectively connected pivotally at their opposite ends to and spaced longitudinally of the jaw and fixed handle, said links being arranged for swinging movement of the jaws toward and away from one another while holding the jaw faces parallel; a center plate slotted longitudinally to receive said guide means, for straight-line movement of the center plate longitudinally of the fixed handle; an actuating lever constituting means connecting the movable handle to the fixed handle for swinging movement, said actuating lever being pivotally connected at opposite ends to the respective handles and being arranged to swing the movable handle longitudinally of the fixed handle toward the jaws on exertion of pressure tending to urge the handles toward one another; direction-reversing means connecting the movable handle and center plate for straight-line movement of the center plate longitudinally of the fixed handle in a direction opposite that given the movable handle; and toggle links articulated to the center plate and jaws respectively and effective to engage the jaws with the work piece responsive to said movement of the center plate.

4. A plier-wrench comprising a fixed handle; a pivot pin and a guide lug carried by and spaced longitudinally of the fixed handle; a movable handle, said movable handle being connected to the fixed handle for swinging movement through a path extending longitudinally of the fixed handle; a pair of jaws provided with parallel, work-engaging faces and articulated to the fixed handle for movement into engagement with a work piece, said jaws being respectively extended longitudinally of the fixed handle, the articulated connection of each jaw to the fixed handle comprising a pair of control links of equal length respectively connected pivotally at their opposite ends to and spaced longitudinally of the jaw and fixed handle, said links being arranged for swinging movement of the jaws toward and away from one another while holding the jaw faces parallel; a center plate having a pair of spaced longitudinal slots receiving the pin and lug respectively, for straight-line movement of the center plate longitudinally of the fixed handle; an actuating lever constituting means connecting the movable handle to the fixed handle for swinging movement, said actuating lever being pivotally connected at opposite ends to the respective handles and being arranged to swing the movable handle longitudinally of the fixed handle toward the jaws on exertion of pressure tending to urge the handles toward one another; direction-reversing means including a main lever rockable on the pivot pin and having pivotal connections at opposite ends thereof to the movable handle and center plate respectively, for imparting straight-line movement to the center plate longitudinally of the fixed handle in a direction opposite that given the movable handle; and toggle links articulated to the center plate and jaws respectively and effective to engage the jaws with the work piece responsive to said movement of the movable handle toward the jaws and said movement of the center plate in an opposite direction.

5. A plier-wrench comprising a fixed handle; a pivot pin and a guide lug carried by and spaced longitudinally of the fixed handle; a movable handle, said movable handle being connected to the fixed handle for swinging movement through a path extending longitudinally of the fixed handle; a pair of jaws having parallel work-engaging faces, said jaws being extended longitudinally of the fixed handle and having articulated connections to the fixed handle for movement of the jaws toward one another into engagement with a work piece, the connections of the jaws to the fixed handle being adapted to preserve the parallel relationship of the jaw faces in selected positions to which the jaws are adjusted toward one another, said jaws being respectively extended longitudinally of the fixed handle, the articulated connection of each jaw to the fixed handle comprising a pair of control links of equal length respectively connected pivotally at their opposite ends to and spaced longitudinally of the jaw and fixed handle, said links being arranged for swinging movement of the jaws toward and away from one another while holding the jaw faces parallel; a center plate having a pair of spaced longitudinal slots receiving the pin and lug respectively, for straight-line movement of the center plate longitudinally of the fixed handle; an actuating lever constituting means connecting the movable handle to the fixed handle for swinging movement, said actuating lever being pivotally connected at opposite ends to the respective handles and being arranged to swing the movable handle longitudinally of the fixed handle toward the jaws on exertion of pressure tending to urge the handles toward one another; direction-reversing means including a main lever rockable on the pivot pin and having pivotal connections at opposite ends thereof to the movable handle and center plate respectively, for imparting straight-line movement to the center plate longitudinally of the fixed handle in a direction opposite that given the movable handle; and toggle links articulated to the center plate and jaws respectively and effective to engage the jaws with the work piece responsive to said movement of the movable handle toward the jaws and said movement of the center plate in an opposite direction.

6. A plier-wrench comprising a fixed handle; a pivot pin and a guide lug carried by and spaced longitudinally of the fixed handle; a movable handle, said movable handle being connected to the fixed handle for swinging movement through a path extending longitudinally of the fixed handle; a pair of elongated jaws extending longitudinally of the fixed handle and having parallel, work-engaging jaw faces at one end thereof; a plurality of control links spaced longitudinally of the handles and of the respective jaws, said links being pivotally connected at one end to the fixed handle and at their other ends to said jaws to swing the jaws toward one another while preserving the parallel relationship of the jaw faces in selected positions to which the jaws are swung; a center plate arranged within the fixed handle between the jaws and having a pair of spaced longitudinal slots receiving the pin and lug respectively, for straight-line movement of

the center plate longitudinally of the fixed handle; an actuating lever constituting means connecting the movable handle to the fixed handle for swinging movement, said actuating lever being pivotally connected at opposite ends to the respective handles and being arranged to swing the movable handle longitudinally of the fixed handle toward the jaws on exertion of pressure tending to urge the handles toward one another; direction-reversing means including a main lever rockable on the pivot pin and having pivotal connections at opposite ends thereof to the movable handle and center plate respectively, for imparting straight-line movement to the center plate longitudinally of the fixed handle in a direction opposite that given the movable handle; and toggle links articulated to the center plate and jaws respectively and effective to engage the jaws with a piece of work responsive to said movement of the movable handle toward the jaws and said movement of the center plate in an opposite direction.

7. A plier-wrench comprising a fixed handle including a pair of rigidly connected, spaced cover plates; a pivot pin and a guide lug secured to and extending transversely between the cover plates and spaced longitudinally of said handle; a movable handle disposed longitudinally of the fixed handle, said movable handle being connected to the fixed handle for swinging movement through a path extending longitudinally of the fixed handle; a pair of elongated jaws extending longitudinally of the fixed handle and having inner end portions extending between the cover plates, said jaws having parallel, work-engaging jaw faces at their outer ends; control links spaced longitudinally of the cover plates and of the respective jaws, said links being pivotally connected at one end to the cover plates and at their other ends to said jaws to swing the jaws toward one another while preserving the parallel relationship of the jaw faces in selected positions to which the jaws are swung; a center plate enclosed by the cover plates and disposed between the jaws, the center plate having a pair of spaced longitudinal slots receiving the pin and lug respectively, for straight-line movement of the center plate longitudinally of the cover plates; an actuating lever constituting means connecting the movable handle to the fixed handle for swinging movement, said actuating lever being pivotally connected at opposite ends to the respective handles and being arranged to swing the movable handle longitudinally of the fixed handle toward the jaws on exertion of pressure tending to urge the handles toward one another; direction-reversing means including a main lever rockable on the pivot pin and having pivotal connections at opposite ends thereof to the movable handle and center plate respectively, for imparting straight-line movement to the center plate longitudinally of the fixed handle in a direction opposite that given the movable handle; and a pair of toggle links extending from each side of the center plate, the toggle links of each pair being pivotally connected at one end to the center plate and at their other ends to the jaw contiguous thereto at locations spaced longitudinally of the center plate and jaws, for shifting the jaw faces into engagement with a piece of work responsive to said movement of the movable handle toward the jaws and said movement of the center plate in an opposite direction.

8. A plier-wrench comprising a fixed handle including a pair of rigidly connected, spaced cover plates; a pivot pin and a guide lug secured to and extending transversely between the cover plates and spaced longitudinally of said handle; a movable handle disposed longitudinally of the

fixed handle, said movable handle being connected to the fixed handle for swinging movement through a path extending longitudinally of the fixed handle; a pair of elongated jaws extended longitudinally of the fixed handle and having inner end portions extending between the cover plates, said jaws having parallel, work-engaging jaw faces at their outer ends; control links spaced longitudinally of the cover plates and of the respective jaws, said links being pivotally connected at one end to the cover plates and at their other ends to said jaws to swing the jaws toward one another while preserving the parallel relationship of the jaw faces in selected positions to which the jaws are swung; a center plate enclosed by the cover plates and disposed between the jaws, the center plate having a pair of spaced longitudinal slots receiving the pin and lug respectively, for straight-line movement of the center plate longitudinally of the cover plates; an actuating lever constituting means connecting the movable handle to the fixed handle for swinging movement, said actuating lever being pivotally connected at opposite ends to the respective handles and being arranged to swing the movable handle longitudinally of the fixed handle toward the jaws on exertion of pressure tending to urge the handles toward one another; direction-reversing means including a main lever rockable on the pivot pin and having pivotal connections at opposite ends thereof to the movable handle and center plate respectively, for imparting straight-line movement to the center plate longitudinally of the fixed handle in a direction opposite that given the movable handle; and a pair of toggle links extending from each side of the center plate, the toggle links of each pair being pivotally connected at one end to the center plate and at their other ends to the jaw contiguous thereto at locations spaced longitudinally of the center plate and jaws, for shifting the jaw faces into engagement with a piece of work responsive to said movement of the movable handle toward the jaws and said movement of the center plate in an opposite direction.

9. In a lock mechanism for a plier-wrench, the combination, with a pair of transversely spaced handles, of a lever pivotally connected at opposite ends to the respective handles and including a latch hook intermediate its ends; a trigger pivoted on one of the handles; a spring operatively associated with the trigger and effective to bias the trigger to a normal handle-unlocking position, said trigger being manually shiftable against the action of the spring to a handle-locking position thereof; a rod carried by the trigger and arranged to be shifted longitudinally of the handle on which the trigger is mounted in one direction responsive to movement of the trigger to said handle-locking position; means on the rod engageable with the hook responsive to movement of the rod in said direction; and spring means operatively associated with said rod to urge the rod in an opposite direction, responsive to pressure exerted manually on the handles tending to urge them toward one another to an extent effective to disengage the hook from said means.

10. In a lock mechanism for a plier-wrench, the combination, with a pair of transversely spaced handles, of a lever pivotally connected at opposite ends to the respective handles and including a latch hook intermediate its ends, said hook being arranged for recessing thereof within one of the handles on shifting of the handles

13

toward one another; a trigger pivoted on the handle within which the hook is recessed; a spring operatively associated with the trigger and effective to bias the trigger to a normal, handle-unlocking position, said trigger being manually shiftable against the action of the spring to a handle-locking position thereof; a rod carried by the trigger and arranged to be shifted on one direction longitudinally of said handle responsive to movement of the trigger to its handle-locking position; a head on the rod engageable with the hook responsive to movement of the rod in said direction, to lock the handles to one another; and spring means operatively associated with said rod to urge the rod in an opposite direction, responsive to further pressure exerted manually on the handles tending to urge them toward one another to an extent effective to recess the hook further within said handle and thereby disengage the hook from the head.

11. In a lock mechanism for a plier-wrench, the combination, with a pair of transversely spaced handles, of a lever pivotally connected at opposite ends to the respective handles and including a latch hook intermediate its ends, said hook being arranged for recessing thereof within one of the handles on shifting of the handles toward one another; a trigger pivoted on the handle within which the hook is recessed; a spring operatively associated with the trigger and effective to bias the trigger to a normal, handle-unlocking position, said trigger being manually shiftable against the action of the spring to a handle-

14

locking position thereof; a block pivoted upon the trigger in spaced relation to the pivot axis of the trigger, so as to swing about said axis on pivotal movement of the trigger; a rod slidably in the block and arranged longitudinally of said handle; a head on the rod engageable with the hook responsive to movement of the rod in one direction, to lock the handles to one another; and a spring on the rod abutting at opposite ends against the head and block respectively and adapted to bias the head into engagement with the hook on swinging of the trigger to handle-locking position, further pressure on said handle being adapted to shift the hook out of engagement with said head, so as to return the trigger, rod, and head to handle-unlocking position under the action of the first named spring.

JOHN JOHNSON.
